UNITED STATES PATENT OFFICE

2,064,459

WINDOW CONSTRUCTION

Emil F. Bumann, Chicago, Ill.

Application April 10, 1936, Serial No. 73,665

6 Claims. (Cl. 20—47)

This invention relates to improvements in windows of the type including a frame having an upper and a lower sash slidably mounted therein and counterbalanced by weights, said improvements more particularly being directed to improved means forming a part of the window frame and sashes, whereby the sashes upon removal of portions of the inner facing strips and of the parting beads may be pivotally swung inwardly from the frame about horizontal axes thereby permitting ready access to be had to the outer surfaces of the window panes to permit cleaning of the same or replacement of the window panes in case they are broken.

15 It is an object of this invention to provide a window construction wherein the window sashes are adapted to be pivotally swung inwardly from the window frame to permit ready access to be had to the outer surfaces of the window panes.

20 It is also an object of this invention to provide a window construction wherein the window frame has the inner facing strips and the parting beads construction to permit portions thereof to be removed from the window frames to permit the window sashes to be equipped with temporary pivots permitting the sashes to be swung downwardly about the pivots to afford ready access to the outer faces of the window glass.

It is an important object of this invention to 30 provide an improved type of window construction consisting of a window frame having counterweighted sashes slidably engaged therein and furthermore having the inner facing strips and the sash parting strips or beads constructed to 35 permit removal of the lower portions of said strips and beads to permit the window sashes to be equipped with removable pivots whereby first the lower sash and then the upper sash may be 40 pivotally swung downwardly about the pivots to permit ready access to be had to the outer surfaces of the window panes to permit cleaning of the same.

Other and further objects of this invention will be apparent from the disclosures in the 45 specification and the accompanying drawing.

The invention (in a preferred form) is illustrated in the drawing and hereinafter more fully described.

On the drawing:

50 Figure 1 is a fragmentary elevational view of the inner side of a window construction embodying the features of this invention.

Figure 2 is a vertical transverse section of the 55 window construction having portions of the inner spacing strip and the parting bead removed

and showing the window sashes equipped with pivot means permitting the same to be pivotally swung inwardly into the dotted line positions to permit access to be had to the outer surfaces of the window sash panes.

Figure 3 is an enlarged fragmentary detail section taken on line III—III of Figure 2.

Figure 4 is an enlarged fragmentary detail section taken on line IV—IV of Figure 1.

As shown on the drawing:

The reference numeral 1 indicates a window frame including an outer sill 2 and an inner sill 3. Slidably mounted in vertical grooves 4 provided on the inner sides of the vertical members of the window frame, are lower and upper window sashes 5 and 6 respectively. The window sashes 5 and 6 have connected thereto sash cords 7 which operate over window pulleys 8 and have counterweights attached to the enclosed ends thereof in the ordinary manner.

The sash grooves 4 are formed between the outer facing strips 9 which extend the whole length of the window opening and inner facing strips each comprising an upper inner facing strip section 10 and a removable lower inner facing strip section 11. The lower ends of the upper inner facing strip sections 10 are beveled as are also the upper ends of the lower inner facing strip sections 11 as indicated at 12 in Figure 1. The removable lower facing strip sections 11 have hidden surfaces 13 thereof (Figure 4). A pair of spaced latch springs 14 are secured to the surfaces 13 of the removable lower facing strip sections 11 by nails 15 or other suitable means. To releasably hold the lower facing strip sections 11 in place against the side members of the window frames, the spring latching members 14 releasably project through openings 16 provided in the vertical members of the frame 1 on opposite sides of the window opening.

Each of the window frame members 17 is provided with a pair of lower and upper internally threaded sockets 18, each of which as clearly illustrated in Figure 3 comprises in detail an internally threaded socket sleeve 19 held in place by means of a retaining sleeve 20 engaged therearound and driven into the frame member 17. The two lower internally threaded socket units 18 are mounted nearer the inner face of the window frame than are the upper pair of internally threaded sockets which are mounted farther in for cooperation with the upper sash as hereinafter more fully described.

The window sashes 5 and 6 are each provided near the lower ends of the inner faces of said

sashes, with a pair of oppositely positioned internally threaded sockets 21 each of which comprises in detail an internally threaded socket sleeve 19 and a retaining sleeve 20 similar to the 5 construction of the socket 18. Apertured face plates 22 are secured to the inner faces of the window sashes 5 and 6 to cover the ends of the socket members 19 and 20 as clearly illustrated in Figure 3.

10 For the purpose of permitting the window sashes to be pivotally swung inwardly about horizontal axes when the lower facing strip sections 11 and the lower removable parting strip sections or beads 23 are removed from the frame, 15 each of the window sash sockets 21 is provided with a removable screw-eye 24. Projecting through each of the eyes of the screw-eyes 24 is a pivot shaft or axis pin 25 provided with a head at the outer end thereof and having the 20 inner end threaded for removable threaded engagement in the internally threaded socket sleeve 19 of the frame socket 18 as illustrated in detail in Figure 3. The grooves 4 of the window frame are separated from one another by means 25 of parting strips or beads each of which comprises a removable lower parting strip section 23 and a permanently mounted upper parting strip section or bead 24. The upper parting strip section 24 is illustrated in Figure 2 from which the 30 lower parting strip section 23 has been removed, but which is shown in place in Figure 3.

Having described in detail the various parts forming the improved features of the window construction the operation thereof will now be 35 briefly described. Normally the window sashes 5 and 6 are slidably engaged in the grooves 4 and the lower parting strip beads 23 and the lower inner facing strip sections 17 are secured in place within the window frame to serve as 40 guides for the window sashes. When it is desired to have access to the outer surface of the lower sash window pane from the inner side of the frame it is only necessary to pull the lower facing strip sections 17 out, in which case the 45 latching springs 16 are compressed and slide through the openings 16 (Figure 4). The lower sash is now raised a slight amount and tilted until the lower sockets 21 are at the same level as the lower sockets 18. Screw-eyes 24 are then 50 threaded into the lower sash sockets 21 and the pivot pins 25 are then projected through the eyes of the screw-eyes 24 and are threaded into the lower sockets 18 provided in the side of the window frame.

55 With the lower sash 5 in the full line position illustrated in Figure 2, the upper end of the lower window sash may be pivotally swung out of the window frame about the horizontal pivots or stud shafts 25, to permit the window cords to be pushed out of the cord grooves of the window sash 60 to allow the window sash to be swung into the dotted line position illustrated in Figure 2, to expose the outer face of the window pane to permit a person within a room to conveniently 65 clean the window pane.

65 After the lower sash has been pivotally swung inwardly into the dotted line position illustrated in Figure 2, the removable parting strip sections or beads 23 are pulled out of the receiving grooves 70 26. The upper sash having been moved downwardly in the frame to permit removal of the parting strips 23, is now equipped with screw-eyes 24. The lower end of the upper sash 6 is now pulled outwardly into the inclined position 75 illustrated in Figure 2 to permit the pivot pins

or stud shafts 25 to be projected through the eyes of the screw-eyes 24, to permit the threaded ends of the stud shafts to be threaded into the upper pair of sockets 18. With the pivot means for the upper sash 6 in position as described, the 5 upper end of the upper sash is now swung downwardly and the sash cords are pushed outwardly to permit the upper end of the upper sash 6 to be swung into the dotted line position illustrated in Figure 2 to afford ready access to the outer 10 face of the window glass of the upper sash.

After the window panes have been cleaned, the window sashes 6 and 5 are returned to their normal position in the reverse order from which they have been released, that is the upper sash 6 and 15 the parting beads 23 are first returned into position, after which the lower sash is returned into its normal position and the cycle of operations is completed by placing the lower facing strip sections 11 back into their normal positions by 20 projecting the latching springs 16 through the frame openings 16.

It will, of course, be understood that various 25 details of construction may be varied through a wide range without departing from the principles of this invention, and it is, therefore, not the purpose to limit the patent granted hereon otherwise than necessitated by the scope of the appended claims.

I claim as my invention:

1. A window construction including in combination a window frame, counterweighted sashes 30 slidably mounted therein, parting beads removably engaged in the frame between the sashes, removable facing strips in the frame, means for releasably holding the facing strips in position, socket means mounted in the frame and on the inner sides of the sashes, screw-eye members releasably engaged in the sockets of said sashes, and stub shaft members projecting through the 35 screw-eye members and releasably engaged in the socket means mounted in the frame to permit the sashes to be pivotally swung downwardly on the inner side of the frame, when the facing strips and the parting beads are removed.

2. A window construction including in combination a window frame including removable parting beads and inner facing strips, sashes 40 slidably engaged in the frame, screw sockets engaged in the sashes and in the frame, said inner facing strips and said parting beads removable from the frame to permit movement of the sashes out of their regular paths of travel, and interfitting threaded members removably engaged in the threaded sockets of the sashes 45 and the frame to permit the sashes to be successively swung downwardly on the inner side of the frame to permit ready access to the outer surfaces of the sashes.

3. A window construction including in combination a window frame having grooves and 50 openings provided in the side surfaces of the window frame opening, window sashes slidably mounted in the frame, parting beads between the sashes removably engaged in the frame 55 grooves, removable inner facing strips, spring latching means secured to the facing strips and removably projecting into the frame openings to hold the facing strips releasably latched in position, and interfitting eye members and headed pins removably engaged in the sashes 60 and in the window frame when the facing strips and the parting beads are removed from the frame to permit the sashes to be successively 70 swung downwardly on the inner side of the frame 75

to afford access to the outer faces of the sashes.

4. A window construction including in combination a frame, facing strips removably engaged therein, a sash slidably mounted in the frame, socket means mounted in the sash and in the frame, said sash adapted to be moved out of its normal path of movement when the facing strips are removed, screw-eyes removably engaged in the socket means of said sash, and threaded pin members projecting through the screw-eyes and releasably engaged in the socket means of said frame to permit the sash to be pivotally swung inwardly about a horizontal axis to permit convenient access to the outer surface of the sash.

5. A window construction including in combination a window frame, a sash slidably mounted therein, sash guide members removably engaged in the frame and adapted to be removed

to permit the sash to be tilted out of its plane of operation, socket members engaged in the sash and in the window frame, eye members removably engaged in said socket means of the sash, and shaft members engaged through the eye members and releasably engaged in the socket means of the frame to permit the sash to be pivotally swung about a horizontal axis to one side of the frame to permit ready access to both sides of the sash.

6. In a window construction of the class described the combination of a window frame having a sash slidably mounted therein, of eye members removably secured to the sash, and shaft members projecting through the eye members and removably secured to the frame to afford horizontal supports for pivotally swinging the sash out of the window frame.

EMIL F. BUMANN.
